ABSTRACT OF THE DISCLOSURE

An improved process for the reduction of color in detergent range olefin sulfonates by the use of two temperature stages and hypochlorite bleach.

This invention relates to a process for the reduction of color in olefin sulfonates in a treatment employing hypochlorite bleach. More particularly it relates to an improved process for color reduction of sulfur trioxide-olefinic hydrocarbon derived sulfonates by the use of two temperature stages in the bleaching process.

It is known to produce sulfonates by the reaction of sulfur trioxide with detergent range olefinic hydrocarbons (see for example U.S. 2,061,619, U.S. 2,061,620 and U.S. 2,094,451) under mild conditions. It is known that in these reactions much undesirable color is concurrently produced and that an appreciable measure of color reduction can be achieved by treatment of the product with hypochlorite bleach (see for example British Pat. 983,056). While the conventional bleaching treatment does improve the olefin sulfonates, the result still leaves much to be desired because the color of the product is in general inferior, for example, to that of alkyl benzenesulfonate detergents long known and accepted by the trade.

It has now been found that the color reduction of substantially neutralized aqueous olefin sulfonate solutions achieved by the addition of hypochlorite bleach and heating is substantially improved when the heating is effected by the use of two temperature stages, the first of which is a relatively high temperature of from about 45 to 90° C., which in the treatment is maintained for a period of about 30 to 90 minutes, and the second of which is a moderate temperature of from about 15 to 35° C., which is maintained for a period of from about 5 to 100 hours. The cooling of the solution from the high temperature range to the moderate temperature range may be accomplished over a period of less than three hours but for best results should be promptly effected, i.e., during a period of less than 30 minutes.

In the bleaching reaction, heating of the sulfonate at the upper temperature range for a longer period of time in a single stage does not yield the improved result obtained in the present process employing two temperature stages. After prolonged time at elevated temperatures, color reversions occur which are not experienced provided that the temperature is reduced sufficiently at or before the time the color reversion commences. At the reduced temperature, surprisingly, the bleaching action has been found to continue without a color reversion in what appears to be a delayed bleaching action at low temperatures. It is clear that several concurrent and possibly subsequent reactions are involved in the bleaching operation.

By definition as used herein by a "detergent range olefinic hydrocarbon" is meant a hydrocarbon which contains a single carbon-carbon double bond and is otherwise saturated and which contains at least 8 and less than 25 carbon atoms.

By "substantial neutralization" as used herein is meant by definition the addition of sufficient sodium hydroxide,

carbonate, oxide or the equivalent inorganic acid-binding-alkali or mixtures thereof to a sulfur trioxide-olefinic hydrocarbon reaction product to adjust the pH of the mixture to a value in the range above 5 and sufficient to yield, 5 after neutralization and hydrolysis, a pH of the resulting mixture in the range 5 to 12. Preferably this pH value is in the range above 7, and more preferably is in the range 8-11. In general the amount of alkali which will be satisfactory for the above neutralization will be in the range 10 0.8 to 1.5 equivalents (acid-base) per mol of sulfur trioxide consumed in preparing the sulfonate.

By the term "mild sulfur trioxide sulfonation conditions" is meant by definition the reaction of sulfur trioxide with an olefinic hydrocarbon in the liquid phase at a temperature in the range 0° C. to 100° C. in which the sulfur trioxide is diluted prior to its introduction into the liquid phase by an inert liquid or inert gas diluent, the concentration of the sulfur trioxide in the resulting mixture being in the range 0.5 to 20 volume percent, and in 15 which for each mol of olefin from about 0.8 to 1.3 mols of sulfur trioxide is used. Air or nitrogen are preferred inert gaseous diluents. The preferred sulfonation temperature is in the range 20° to 50° C.

In a preferred embodiment of the invention sodium 25 hypochlorite is added to a substantially neutralized (pH ~7-11) aqueous sulfonate mixture obtained from the reaction of an n-C₁₂C₂₀-alkene-1 molecular mixture with sulfur trioxide under mild sulfonation conditions. For each 100 parts of the sulfonate 3 parts by weight of sodium hypochlorite is added to the mixture which is then 30 heated to 75-85° C. for a period of 40-80 minutes. Thereafter the reaction mixture is cooled during a period of less than 30 minutes by a suitable means to 20-25° C. and maintained at this temperature for a period of 5-10 35 hours. Excess bleaching agent is then destroyed at the end of the second bleaching step. This may be accomplished by adding a reducing agent, e.g. sodium bisulfite. Thereafter the bleached olefin sulfonate is ready for the 40 succeeding processing stage which is ordinarily a concentration stage and/or a spray drying stage for the recovery of the detergent active.

The color of detergent range olefinic hydrocarbon sulfonates in general is improved by the present process. The sulfonates containing 10 to 22 carbon atoms in the 45 molecule, preferably 12 to 20 carbon atoms are preferred feeds for the process. Molecular mixtures are included in the foregoing. All molecular types, including straight chain, branched chain, cycloaliphatic and combinations thereof are satisfactory olefin sulfonate feeds. Both internal and terminal olefinic hydrocarbons are satisfactory.

Representative olefin-sulfonate feeds for the present process include those obtained from C₁₀-C₂₂ cracked wax α-olefins, as well as individual molecular range fractions thereof, C₁₅-C₁₈-α-olefins, C₁₀-C₂₂ internal n-olefins, C₁₅-C₁₈ internal n-olefins; branched chain alkenes such as 5-methyl-1-hexadecene and the like methyl substituted n-alkenes; other olefins such as cyclooctene, cyclododecene, vinylcyclohexane, dodecene-2, hexadecene-4, terpenes, eicosene-1, nonene-1, octadecene-5, 4-methylcyclooctene, 55 hexadecene-2, n-octene-1, n-dodecene-2, tetracosene-1, hexadecene-4, 2,2-dimethylpentadecene-6, n-propylcyclohexene-3 and the like, partially isomerized n-α-olefin, i.e., mainly n-alkene-2's, and the like monoolefinic, non-aromatic hydrocarbons.

Minor amounts of inert impurities such as saturated hydrocarbons may be present in the olefinic hydrocarbon precursor of the subject olefin sulfonates. Similarly the presence of minor amounts (less than 50 weight percent) of alkylbenzene sulfonate detergent in the olefin sulfonate does not interfere, and possibly may be advantageous, 65 with the instant bleaching process.

The time-temperature relationships for both steps of the instant bleaching process are conventional. That is, as the temperature is increased, shorter reaction times are required. Thus for the time-temperature range couples disclosed above, the shorter times correspond to the higher temperatures in each instance.

The hydrochlorite bleach used in the invention is preferably sodium hypochlorite although alkali metal and alkaline earth metal hypochlorites may be used. The sodium bleach is an article of commerce and least costly. On the other hand, the alkaline earth bleaches, such as the calcium salt, can be used but they are less desirable by reason of the unfavorable solubility parameter.

The amount of bleach relative to the sulfonate which is desirably used varies, depending: (1) upon the intensity of the color of the sulfonate; (2) the particular bleach to be used; and (3) in lesser degree, the temperature to be employed. In general, a satisfactory amount is in the range from about 0.25 to 5 parts (weight) per 100 parts (weight) of the sulfonate. Larger relative amounts, for example 100 parts of bleach, may be used without substantial adverse effects, but in general such use is uneconomical, in addition the excess hypochlorite introduces sodium chloride into the product.

The subject olefin sulfonates are generally neutralized and hydrolyzed utilizing aqueous sodium hydroxide or the equivalent. Aqueous solutions are therefore preferred for the bleaching. However, polar solvents relatively stable to the bleach may also be used such as aqueous alcohol solutions, and the like.

The concentration of the sulfonate in the bleaching solution may vary widely. As a practical matter, at least 10 weight percent solution is desirably employed. All of the sulfonate need not be in solution for the bleaching, thus bleaching is effective where an aqueous slurry of the sulfonate is used. For mechanical and economical reasons, best results in general follow from the use of aqueous solutions containing from about 20 weight percent up to the saturation value, i.e., usually in the range 50-65 weight percent, of the sulfonate.

The pH of the reaction mixture during the bleaching reaction may be neutral or basic and preferably above 7. The bleaching may be effected concurrently with hydrolysis.

The following examples further illustrate the invention:

In the examples to follow representative preparations (Examples 1 and 8) of detergent range sulfonates suitable for use in the instant process are described; and in the balance of the examples portions are treated as described. The color of the treated and untreated solutions was determined by the use of a Klett-Summerson Photoelectric Colorimeter using aqueous sulfonate solutions containing 5% (weight) of the olefin sulfonate.

EXAMPLE 1

Representative preparation of alpha olefin sulfonate feed for bleaching

The reactor used for this sulfonation consisted of a continuous falling film-type unit in the form of a vertical water jacketed tube. Both the olefin and the SO_3 -air mixture were introduced at the top of the reactor and flowed concurrently down the reactor. At the bottom the sulfonated product was separated from the air stream.

The feed stock for this example was a 1-olefin blend having the following composition by weight: 1% tetra-ecene, 27% pentadecene, 29% hexadecene, 28% heptadecene, 14% octadecene, and 1% nonadecene. This material was charged to the above described apparatus at a rate of 306 pounds/hour. At the same time 124.2 pounds/our of SO_3 diluted with air to 3% by volume was introduced into the top of the reactor. The apparatus was cooled with water in order to maintain the temperature of the product within the range of 43-46° C. Under these

conditions the average residence time was less than two minutes.

After passing out of the reactor the air-free sulfonated product was mixed with 612 pounds/hour of 11.2% aqueous caustic. The resulting slurry was hydrolyzed by heating at 145-150° C. in a tubular reactor at an average residence time of 30 minutes. In this way 463 pounds/hour of olefin sulfonate was obtained as a 45% aqueous solution having a pH of 10.8. The yield was 95.5%.

A portion of this product was analyzed and shown to be made up of the sodium salts of alkene sulfonic acids, hydroxyalkane sulfonic acids, with a minor proportion of disulfonic acids.

EXAMPLE 2

A portion of the product from Example 1 was diluted with water to yield a 5 percent (weight) solution (sample 1). This solution had a color value of 680 Klett units (40 mm. cell).

A second portion of the product from Example 1 was diluted with water to yield a 25 percent (weight) solution and 600 grams of solution of this concentration were charged to a glass reaction vessel.

The reactor and contents were heated up to about 83° C. at which time 38.2 grams of aqueous sodium hypochlorite (11.8% hypochlorite by weight) were added. The mixture was maintained at 80±2° C. for one hour with stirring after which time a 21.3 gram sample was removed from the flask. Distilled water was added to cool and dilute the solution to a 5 weight percent concentration of olefin sulfonate active. The resulting solution was then filtered. The color of the dilute solution was measured in a 40 mm. colorimeter cell and found to be 132 Klett units.

EXAMPLE 3

One-half of the solution remaining after removal of the sample in Example 1 was maintained at 80±2° C. for 5 additional hours and the color value determined as in Example 1. It was 217.

EXAMPLES 4-7

In the manner as described above and for the periods stated in the following table additional color values were determined.

TABLE.—COLOR VALUES FOR BLEACHED¹ OLEFIN SULFONATES

Sample No.	Treatment				Color Klett	
	First stage		Second stage			
	Temp. °C.	Hours	Temp. °C.	Hours		
1	(2)	-----	-----	-----	680	
2	80	1	-----	-----	132	
3	80	6	-----	-----	217	
4	80	25	-----	-----	212	
5	80	1	22	5	124	
6	80	1	22	24	114	
7	80	6	22	21	200	

¹ Bleaching with 3% (weight, based on active) sodium hypochlorite.

² No treatment.

EXAMPLE 8

The feed stock for this sulfonation was a 1-olefin mixture having the same composition as in Example 1. The reactor was similar to that of Example 1, except smaller in size. The 1-olefin mixture was fed to the sulfonates at a rate of 4.37 gram/min. At the same time, 1.88 gram/min. of SO_3 (diluted with nitrogen to 3% by volume) was introduced into the top of the reactor. The temperature was maintained at 80° C. Under these conditions the average residence time was less than two minutes.

After passing out of the reactor, the sulfonates product was collected in 30-minute portions. These were each mixed with 353 grams of 8% aqueous sodium hydroxide. The resulting slurry was hydrolyzed as in Example 1. After hydrolysis the product was diluted with water to an 18.1% concentration. A portion of this solution was

further diluted to 5% (weight) and filtered. The color of this solution in a 20 mm. cell was 760 Klett units.

EXAMPLE 9

To 138.5 grams of the 18.1% solution of Example 8 which had been heated to about 53° C., there was added 6.64 grams of an 11.3% (weight) aqueous sodium hypochlorite solution. The mixture was stirred at 50±2° C. for one hour. At the end of this time, distilled water was added to cool and to dilute the olefin sulfonate solution to 5% concentration. This solution was filtered, and the color of it was found to be 340 Klett units when measured in a 40 mm. cell.

EXAMPLE 10

The dilute and treated solution of Example 9 was cooled and stored in a glass flask for 9 days at 22 to 25° C. At the end of this time the color (40 mm. cell) was 137 Klett units.

EXAMPLE 11

Another batch of olefin sulfonate was prepared by the procedure of Example 8. A portion of this material was diluted to produce a 25% solution. It was then bleached in the manner of Example 9. At the end of one hour the bleached solution was cooled to room temperature. Portions of this solution were periodically removed, diluted to 5% and analyzed for color. The color values for the 5% solution were as follows.

Time (days):	Color ¹
0	228
1	155
2	115
3	95
6	93

¹ Klett units in a 20 mm. cell.

EXAMPLE 12

A portion of the crude sulfonate of Example 11 was bleached as before except that the temperature was maintained at 80±2° C. for one hour and then cooled to room temperature, i.e. 20-22° C. and maintained at this temperature. The color values for the 5% solutions were as follows:

Time (days):	Color ¹
0	137
1	104
2	96
3	95

¹ Klett units in a 20 mm. cell.

The foregoing examples demonstrate that improved reduction of color in the hypochlorite bleaching of olefin sulfonates can be obtained provided that two temperature stages are employed in the manner described above.

What is claimed is:

1. In the reduction of the color of an aqueous sulfonate by adding hypochlorite bleach and heating the resulting mixture, said sulfonate having been obtained by the reaction of sulfur trioxide with a detergent range olefinic hydrocarbon under mild sulfur trioxide sulfonation conditions followed by substantial neutralization with strong alkali, and wherein for each 100 parts by weight of the sulfonate from about 0.25 to 5 parts of the bleach is present in the mixture, the improvement which comprises heating said mixture to an elevated temperature

in the range from about 45 to 90° C. for a period in the range from 30 to 90 minutes, thereafter cooling said heated mixture to a moderate temperature in the range from about 15 to 35° C. and maintaining said lower temperature for a period in the range from about 5 to 100 hours, said cooling from the elevated range to the moderate range being effected in a period of less than 5 hours.

2. The process as in claim 1 further characterized in that said elevated temperature range is from about 75 to 85° C., said lower temperature is in the range 20 to 25° C., said period at the elevated temperature is in the range 40 to 80 minutes, said period at the lower temperature is in the range 5 to 10 hours, and said cooling is effected during a period of time which is less than 30 minutes.

3. The process as in claim 2 further characterized in that said olefin sulfonate is selected from the group consisting of n-C₁₂-C₂₀-alkene sulfonates and mixtures thereof.

4. The process as in claim 3 further characterized in that said alkene sulfonate is an internal sulfonate.

5. The process as in claim 3 further characterized in that said alkene sulfonate is an internal olefin sulfonate.

6. The process as in claim 1 further characterized in that said neutralization is to a pH value in the range from about 7 to 11.

7. In the reduction of the color of an aqueous sulfonate by adding hypochlorite bleach and heating the resulting mixture, said sulfonate having been obtained by the action of sulfur trioxide with a detergent range olefinic hydrocarbon under mild sulfur trioxide sulfonation conditions followed by substantial neutralization with strong alkali, and wherein for each 100 parts by weight of the sulfonate about 3 parts of the bleach is present in the mixture, the improvement which comprises heating said mixture to an elevated temperature in the range from about 75 to 85° C. for a period in the range from 40 to 80 minutes, thereafter cooling said heated mixture to a moderate temperature in the range from about 20 to 25° C. and maintaining said lower temperature for a period in the range from about 5 to 10 hours, said cooling from the elevated range to the moderate range being effected in a period of less than 30 minutes.

8. The process as in claim 7 further characterized in that said olefin sulfonate is selected from the group consisting of terminal n-C₁₂-C₂₀-alkene sulfonates, of internal n-C₁₂-C₂₀-alkene sulfonates, and of molecular mixtures thereof.

9. The process as in claim 7 further characterized in that said neutralization is to a pH value in the range from about 7 to 11.

10. The process as in claim 7 further characterized in that said elevated temperature is about 80° C. and said moderate temperature is about 20-25° C.

11. The process as in claim 7 further characterized in that said elevated temperature is about 53° C. and said moderate temperature is about 20-25° C.
